(57) **CLAIM**

The ornamental design for a side flashlight mount, as shown and described.

DESCRIPTION

FIG. 1 is a top isometric view of a side flashlight mount, showing my new design;

FIG. 2 is a bottom isometric view of the side flashlight mount shown in FIG. 1;

FIG. 3 is a front elevational view of the side flashlight mount shown in FIG. 1;

FIG. 4 is a right side elevational view of the side flashlight mount shown in FIG. 1;

FIG. 5 is a left side elevational view of the side flashlight mount shown in FIG. 1;

FIG. 6 is a rear elevational view of the side flashlight mount shown in FIG. 1;

FIG. 7 is a top plan view of the side flashlight mount shown in FIG. 1; and,

FIG. 8 is a bottom plan view of the side flashlight mount shown in FIG. 1.

The broken lines and the areas within them represent portions of the side flashlight mount that form no part of the claimed design.

1 Claim, 6 Drawing Sheets
